DESIGN FOR AN APPOINTMENT WATCH PIN OR SIMILAR ARTICLE

Abraham Fingerhut, New York, N. Y.

Application June 10, 1941, Serial No. 101,374

Term of patent 3½ years

To all whom it may concern:

Be it known that I, Abraham Fingerhut, a citizen of the United States and residing in Manhattan, in the city, county, and State of New York, have invented a new, original, and ornamental Design for an Appointment Watch Pin or Similar Article, of which the following is a specification, reference being had to the accompanying drawing, forming part thereof, wherein pin or similar article showing my new design.

Fig. 1 is a front view of an appointment watch

Fig. 2 is a rear view thereof.

Fig. 3 is an edge elevational view looking upwardly on the disclosure in Fig. 1.

I claim:

The ornamental design for an appointment watch pin or similar article, substantially as shown.

ABRAHAM FINGERHUT.
